Patented May 3, 1904.

UNITED STATES PATENT OFFICE.

EDWARD DODD CONKLIN, OF NEWARK, NEW JERSEY, ASSIGNOR TO THE
WHITEHEAD & HOAG COMPANY, OF NEWARK, NEW JERSEY, A COR-
PORATION OF NEW JERSEY.

DESIGN FOR A PAPER-WEIGHT.

SPECIFICATION forming part of Design No. 36,904, dated May 3, 1904.

Application filed March 16, 1904. Serial No. 198,492. Term of patent 7 years.

To all whom it may concern:

Be it known that I, EDWARD DODD CONKLIN, a citizen of the United States, residing in the city of Newark, State of New Jersey, have invented a new, original, and ornamental Design for a Paper-Weight, of which the following is a specification, reference being had to the accompanying drawings, in which—

Figure 1 is a top plan view thereof. Fig. 10 2 is a side view thereof.

What I claim is—

The ornamental design for a paper-weight as shown.

EDWARD DODD CONKLIN.
